F. P. HOWARD,
CARBON REMOVING MEANS FOR INTERNAL COMBUSTION ENGINES.
APPLICATION FILED FEB. 28, 1920.

1,395,571.

Patented Nov. 1, 1921.

BY G. H. Davis
ATTORNEY.

UNITED STATES PATENT OFFICE.

FRANK P. HOWARD, OF LISBON, NEW HAMPSHIRE.

CARBON-REMOVING MEANS FOR INTERNAL-COMBUSTION ENGINES.

1,395,571.

Specification of Letters Patent.

Patented Nov. 1, 1921.

Application filed February 28, 1920. Serial No. 362,096.

To all whom it may concern:

Be it known that I, FRANK P. HOWARD, a citizen of the United States, residing at Lisbon, in the county of Grafton and State 5 of New Hampshire, have invented certain new and useful Improvements in Carbon-Removing Means for Internal-Combustion Engines, of which the following is a specification.

10 This invention relates to means for removing the carbon from the cylinders of internal combustion engines, and more particularly to means employing a solvent for this purpose.

15 It is well known that certain liquids, and especially hydrocarbons, such as kerosene, have a solvent effect on such carbon deposits, and are efficacious in cleaning the cylinders of internal combustion engines, 20 but great difficulty has heretofore been experienced in properly introducing such substances into the cylinders. Attempts have hitherto been made to inject cleaning liquids through spark plug openings, or by means of 25 priming cups, but liquids so introduced are not properly distributed, and do not produce satisfactory results.

30 It is the primary object of the present invention, therefore, to provide simple, convenient, and efficient means for effectively introducing into an engine manifold a suitable hydrocarbon or other substance for cleaning the cylinders.

35 A further object is to provide means whereby such cleaning agent may be supplied to the manifold in either liquid or vapor form, as desired, the vapor being of a character either the same as or different from the liquid.

40 A still further object is to provide an improved mechanical construction of vapor forming and liquid delivery apparatus peculiarly adapted for the above purposes.

45 With the above and other objects in view, the invention consists in the construction, combination and arrangement of parts hereinafter described and claimed, and illustrated in the accompanying drawing, in which:—

50 Figure 1 is a longitudinal vertical section through my improved device, parts being shown in elevation and a portion of an en-

gine manifold being illustrated in dotted lines;

Fig. 2 is a side elevation of my improved 55 device, and

Fig. 3 is a front elevation thereof, showing the manner of supplying liquid thereto.

Referring to the drawings in detail, my improved device comprises a container or 60 receptacle 1 preferably made of metal and shown as rectangular in shape. This container has a bottom 2 provided with an annular flange 3 within which snugly fits the upper end of a cup 4 preferably formed of 65 glass. A gasket 5 of rubber or the like may be employed to insure a tight seal between the upper edge of the cup 4 and the container 1.

The cup 4 is supported by means of a 70 saucer or stirrup 6 in which it rests and the stirrup is held by means of a strap 7 passing under the same, the free ends of which are secured to plungers 8 working freely in guide tubes 9 extending through the container or receptacle 1. The upper ends of these tubes are preferably closed as by means of removable plugs 10. The upper end of each plunger 8 is provided with an enlarged head 12, and each tube 9 carries an inwardly 80 extending annular shoulder 13. Between the head 12 and shoulder 13 is a helical spring 11, the resiliency of which serves to exert a yielding upward pull on the strap 7, thus urging the cup 4 against the gasket 85 5 and holding it firmly in position, notwithstanding the severe vibration to which it is subjected.

Extending vertically down through the receptacle 1 is an air inlet tube 14 having 90 an enlarged screw threaded portion 15, engaging the top of the receptacle. Thus tube passes down through the bottom of the receptacle into the cup 4, its end terminating a short distance above the bottom of the 95 cup. The bottom 2 of the receptacle is provided with a plurality of perforations 16, so that the interior of the cup 4 is in free communication with the interior of the receptacle. The cup and receptacle when in 100 use are partially filled with a suitable liquid, such as kerosene, to a height as indicated for example at α in Fig. 1. The receptacle is further provided with a drain cock 17

and a waste or overflow outlet 18. Screw bolts 19 having nuts 20 are also preferably provided so that the device may be conveniently attached to the dash board or other part of an automobile.

Surmounting the receptacle 1 is an air dome chamber formed by an annular upstanding flange 21 and an inverted cup or cap 22 snugly fitting such flange. The top 10 wall of the container 1 is provided with perforations 23 affording communication between the interior of the container and the dome or chamber above described.

Carried by the wall of the air dome or 15 cap 22 is a pipe 24 terminating on the inside of the cup 22 in a beveled end 24^a. A pipe or tube 25, which may be of copper, rubber or other suitable material, extends from the pipe 24 to the engine manifold 20 26 at a point between the carbureter and cylinders, the passage of fluid through such pipe being controlled by means of a pet cock 25^a, operated by a pull rod 25^b in any suitable manner.

25 Obviously when this pet cock is opened and the engine is running, the suction created by the engine will cause air to flow down through the tube 14 and bubble up through the liquid contained in the receptacle, such bubbles being readily visible 30 through the glass cup 4. This produces a vaporization of the liquid, and the vapor passes up through the perforations 23 and thence through the pipes 24 and 25 to the 35 engine cylinders, where it assists in cleaning and removing the carbon therefrom.

If it is desired to supply kerosene or other substances in liquid form to the manifold, the upper end of the tube 14 is closed by 40 means of a plug 14^a, as shown in Fig. 3. A short piece of flexible hose 29 is then attached to a nozzle 27 carried by the cap 22 immediately above the end of pipe 24, the protecting cap 28 being, of course, removed. 45 The free end of the hose 29 is immersed in kerosene or other liquid contained in a cup 30, which may be held in the hand or otherwise suitably supported. The suction of the engine will, therefore, cause liquid to be 50 drawn in through the hose 29 and nozzle 27, from which it will pass into the pipe 24 and be conveyed to the manifold.

This operation of supplying liquid to the engine should be performed, of course, when 55 the automobile is not in motion, and while the engine is either running slowly or being cranked.

It will be understood that if it is desired to remove the glass cup 4, this may be ac-

complished by pulling down on the stirrup 60 6, and swinging it to one side, the springs 11 yielding sufficiently to permit the edge of the stirrup to clear the bottom of the cup.

It will thus be seen that I have provided a simple and efficient device whereby either 65 liquid or vapor may be supplied to an engine manifold as required, and thence distributed to the cylinders and it is thought that the many advantages of my invention will be readily appreciated without further discussion. 70

What I claim is:

1. The combination with a liquid receptacle having two communicating compartments, one partially filled with liquid, and 75 the other having a suction pipe extending therefrom, and provided with a liquid inlet, an air inlet pipe discharging below the level of the liquid in said first mentioned compartment, and means for closing said air inlet 80 pipe so as to cause said suction pipe to draw in liquid from another source through said liquid inlet.

2. A hydrocarbon vapor generator comprising a receptacle partly filled with liquid 85 hydrocarbon, a suction pipe extending from the upper part of said receptacle, a glass cup fitted in the bottom of said receptacle and communicating therewith, and an air inlet tube passing down into said receptacle and 90 terminating in said cup, whereby suction through said pipe causes air to flow in through said tube and bubble up through the liquid, such bubbles being visible through said glass cup. 95

3. A hydrocarbon vapor generator comprising a receptacle partly filled with liquid hydrocarbon, a suction pipe extending from the upper part of said receptacle, a detachable glass cup fitted to the bottom of said 100 receptacle and communicating therewith, and a stirrup supporting said cup.

4. A hydrocarbon vapor generator comprising a receptacle partly filled with liquid hydrocarbon, a suction pipe extending from 105 the upper part of said receptacle, a cup fitted in the bottom of said receptacle and communicating therewith, a stirrup in which said cup rests, and means for resiliently supporting said stirrup so as to hold said cup 110 in position.

In testimony whereof I affix my signature in presence of two witnesses.

FRANK P. HOWARD.
